UNITED STATES PATENT OFFICE.

CHRISTOPHER C. TRACY, OF BROOKLYN, ASSIGNOR TO THE COLWELL LEAD COMPANY, OF NEW YORK, N. Y.

MACHINE FOR MAKING LEAD PIPE.

SPECIFICATION forming part of Letters Patent No. 340,465, dated April 20, 1886.

Application filed December 28, 1885. Serial No. 186,876. (No model.)

To all whom it may concern:

Be it known that I, CHRISTOPHER C. TRACY, of Brooklyn, in the county of Kings and State of New York, have invented a new and Improved Lead-Pipe Machine, of which the following is a full, clear, and exact description.

The lead-pipe machines in use, and to which my invention is applicable, comprise a hydraulic press, a die-holder, and receiving-reservoir. 10 In the receiving-reservoir is placed a mandrel which forms the bore of the pipe.

Difficulty is now experienced in removing the mandrel from the receiving-reservoir and replacing it with a larger or smaller one, which 15 must be done to form pipes of different thicknesses or of different-sized bore.

The object of my invention is to overcome this difficulty; and to this end my invention consists, principally, in making the receiving-20 reservoir movable, so that it may be moved to and from the point of alignment with the die-holder, which not only facilitates the removal of the mandrel from the receiving-reservoir, but also the pouring of the molten 25 metal into the receiving-reservoir from which the pipe is to be formed.

My invention also consists of means for shifting the receiving-reservoir and guideways or tracks on which the receiving-reservoir moves; 30 and the invention further consists of the construction, arrangement, and combination of parts, all as hereinafter described and claimed.

Reference is to be had to the accompanying drawings, forming a part of this specification, 35 in which similar letters of reference indicate corresponding parts in all the figures.

Figure 1 is a side elevation of the lead-pipe machine having my improvements applied thereto, two of the pillars being broken away 40 opposite the die. Fig. 2 is a sectional elevation taken on the line $x-x$ of Fig. 3; and Fig. 3 is a sectional plan view taken on line $y-y$ of Fig. 2, a portion of the receiving-reservoir being broken away.

45 A represents the hydraulic press, and B the piston or plunger thereof. Rising from the top of the press are four pillars or columns, C, to the upper ends of which is firmly secured the head-plate D.

50 In line with the aperture d of the plate D is

secured, to the under surface of the plate, a die-holder, E.

F represents the receiving-reservoir, which is made movable to and from the point immediately below the die-holder, as indicated in Figs. 1 and 2. The receiving-reservoir in this instance is mounted upon the base or carriage F', which forms the bottom of the receiving-reservoir and runs upon or between ways or flanges G G, which insure the proper 55 registering of the receiving-reservoir with the die-holder when the former is moved into position below the die-holder for forming the pipe. The flanges or ways in this instance are formed or secured upon the intermediate 60 plate or table, H, secured upon the upper end of the plunger B of the press. This intermediate plate, H, will be used when my invention is to be applied to machines already in use; but when machines are to be constructed to 65 receive my invention the plate or table H may be omitted, and the flanges G formed or secured directly upon or to the upper end of the plunger. 70

The receiving-reservoir may be moved from the position shown in Fig. 1 to that shown in 75 Figs. 2 and 3 by hand, or by separate levers, or by any other suitable means; but for shifting the receiving-reservoir I prefer to use a capstan, I, provided at its ends with cranks $a a$, which are connected by the connecting-rods $b b$ with the base-plate or carriage F', so that by turning the capstan in its bearings, by means of a lever or otherwise, the 80 cranks and connecting-rods will act to draw the receiving reservoir out from under the die-holder or force it back in line with the die-holder, according to the direction in which the capstan is turned. The capstan I is journaled in journal-blocks c, held in the frame 85 d d, secured upon the upper surface of the plate H. The journal-blocks c are made adjustable in the frames d by means of opposite set-screws, e e, to take up the wear, and so that the capstan I may be moved slightly in the frames d, in order that accurate registration of 90 the receiving-reservoir and die-holder may always be secured. When the capstan is turned so that the cranks a occupy the position shown in Fig. 1, they are stopped in that position by 95 small projections or blocks f, which are of 100

such height that the connection between the cranks and connecting-rods stand exactly in line with the axis of the capstan and the receiving-reservoir connections, thus locking the die in proper position under the die-holder.

In the receiving reservoir F is secured, in the ordinary manner, the mandrel J, which penetrates the die-holder and forms the bore of the pipe when the receiving-reservoir is elevated by the hydraulic press. When the mandrel J is to be removed from the receiving-reservoir, and a larger or smaller one put in its place, the capstan I will be operated and the receiving-reservoir moved out from under the die-holder to the position shown in Figs. 2 and 3, in which position the mandrel may be easily reached and removed without interference with the die-holder, and another mandrel as easily put in place.

In operation, the proper sized mandrel being in place in the receiving-reservoir, the receiving-reservoir will be filled with molten lead and then moved by operating the capstan to a point immediately underneath the die-holder. Then water will be admitted to the press A, and the receiving-reservoir lifted in contact with and to inclose the die holder. The entrance of the die-holder into the receiving-reservoir forces the molten metal therein

through the aperture g of the die-holder and 30 forms it around the mandrel J into pipe.

Having thus fully described my invention, what I claim as new, and desire to secure by Letters Patent, is—

1. The receiving-reservoir F, placed upon 35 the ways G, in combination with the capstan I, having cranks connected by suitable connecting-rods to the receiving-reservoir, substantially as described.

2. The combination, with the piston of the 40 press, of the intermediate plate, H, and receiving-reservoir F, placed upon or in the ways G, formed or secured upon the plate H, substantially as described.

3. The capstan I, held in adjustable bearings and connected with the receiving-reservoir F, for moving and adjusting the same, substantially as described. 45

4. The combination, with the movable receiving-reservoir F and capstan I, connected 50 by cranks a and rods b with the receiving-reservoir, of stops f, arranged to stop the cranks a and rods b in line with the axis of the capstan, as and for the purposes set forth.

CHRISTOPHER C. TRACY.
